UNITED STATES PATENT OFFICE.

GEORGE A. BURNHAM, OF SAUGUS, MASSACHUSETTS, ASSIGNOR TO S. B. CONDIT, JR.,
OF BOSTON, MASSACHUSETTS.

TIME-LIMIT DEVICE FOR ELECTRIC SWITCHES.

979,256.

Specification of Letters Patent. Patented Dec. 20, 1910.

Application filed February 3, 1910. Serial No. 541,721.

To all whom it may concern:

Be it known that I, GEORGE A. BURNHAM, of Saugus, county of Essex, and State of Massachusetts, have invented an Improvement in Time-Limit Devices for Electric Switches, of which the following is a specification.

This invention relates to time-limit devices for electric-switches, and has for its object to provide the controlling-device for the electric-switch with means adapted to be operated at a variable speed, whereby the time consumed in operating it may be varied automatically; also to provide a timed operating-device for the controlling-device for the electric-switch, with means, such, for instance, as an electric-motor having the general characteristics of a series type of motor, for operating it at a variable speed, according to the strength of the current passing through it; also, to improve the construction of the timed operating-device whereby its normally disengaged parts may be brought into engagement by mechanical means; also, to provide for operating the mechanical means employed for moving the parts of the timed operating-device into engagement by means employed for subsequently operating the timed operating-device, whereby a single actuator may be employed for accomplishing these results; also, to provide means for re-setting the parts when the motor or other actuator ceases to operate; also, to provide the circuit with an overload-relay having means for normally shunting the time-limit device, and also a switch adapted to control the circuit of the controlling-device electric-switch, whereby said circuit may be controlled by both the time-limit device and the overload-relay, in the former instance the circuit being operated by a slight overload after a prolonged period of time, and in the latter instance by a heavy overload instantly.

Figure 1 is a side elevation of a time-limit device for electric-switches embodying this invention, the parts being in their normal positions of rest. Fig. 2 is a detail of a portion of the device shown in Fig. 1, the parts being in the positions they will occupy when in operation. Fig. 3 is a side elevation of an overload relay adapted to be employed in connection with the time-limit device. Fig. 4 is a diagram illustrating the inven-

tion as applied to a polyphase system of electrical distribution. Fig. 5 is a similar diagram illustrating the invention as applied to a single-phase system of electrical distribution.

Referring to Fig. 4, wherein a three-phase system is illustrated, *a*, *b*, *c*, representing the three phases of the circuit, two current-transformers, *d* and *d'*, are respectively represented as installed in circuit-wires *a* and *c*, and overload-relays *d²*, *d³*, are arranged in the transformer circuit, with one end of each coil connected respectively to the current-transformers by circuit-wires 2, and the other ends thereof connected together by circuit-wire 3. The armatures or cores of the relays have connected with them, by rods *d⁹* or otherwise, suitable contact-plates *d⁴*, which normally rest on contacts *d⁶*, *d⁸*, which are connected by circuit-wires 4, respectively with circuit-wires 5 leading to the current-transformers, and are connected together by a circuit-wire 6. The circuit-wire 6 is also connected with a circuit-wire 3 by a circuit-wire 7. With this arrangement the current normally passes through the contact-plates *d⁴*, *d⁸*, and contacts on which they rest.

As an actuator for the time-limit device I prefer to employ an electric-motor, *e*, of the series type, or one having the general characteristics of a series type of motor, whereby the speed of its armature is variable according to the strength of the current, but, so far as some features of my invention are concerned, any other type of electric-motor or any other kind of motor may be employed. As here shown said motor is connected by circuit-wires 8 and 9 leading to the circuit-wires 5, 5, and hence is arranged in series with the overload-relays, but when the contacts *d⁴*, *d⁸*, are closed, which is the position they normally occupy, said motor is shunted, and its armature is normally at rest. The rotatable armature *e'* of said motor has a shaft *e²*, constituting the actuating-member, which is here shown as formed or provided with a threaded portion *e³* for the engagement therewith of a suitable operating-device for the controlling-device of an electric-switch, whereby said operating-device may be moved at a variable speed. Said operating-device, as here shown, comprises a worm-wheel *e⁵*, jour-

naled at the extremity of the arm e^6 of a bell-crank lever, which is pivoted at e^7 to a suitable support, the other arm e^8 of said lever having a bifurcated end adapting it 5 to engage a pin e^9 extended from a sleeve e^{20} arranged on a sliding-collar e^4 , arranged on the motor-shaft near the threaded portion thereof. As said bell-crank lever is moved on its pivot, said worm-wheel is moved into 10 and out of engagement with the worm e^3 . To move the bell-crank lever, and thus control the engagement of the worm-wheel and worm, the collar e^4 is moved along on the shaft, and, to accomplish this result, a device, acting by centrifugal force, or other 15 means operated mechanically by the shaft, is employed. Said mechanical device, as here shown, consists of a collar f , pinned or otherwise secured to the shaft, bearing a pair of ears f' , f'' , to which are loosely or 20 pivotally connected a pair of links f^2 , f^2 , which are loosely or pivotally connected to arms f^3 , f^3 , which are loosely or pivotally connected at one end to ears on the sliding-collar e^4 , and bear at their extremities balls f^4 , f^4 . Said sliding-collar is movable horizontally on the shaft and may be kept in 25 position by a spline, and a spring f^5 is arranged on the shaft between the fixed and movable collars, acting to force the movable collar away from the fixed collar, but yielding when the shaft is rotated, and the ball-carrying arms are swung outwardly by centrifugal action. When the shaft is 30 at rest, the ball-carrying arms resume a position close to the shaft, and the bell-crank lever is moved to disengage the worm-wheel from the worm, but when the shaft is being rotated and the sliding-collar is moved along 35 on the shaft mechanically by the outwardly moving ball-carrying arms, due to centrifugal action, said bell-crank lever is moved to cause the worm-wheel to engage the worm, and said engagement will continue 40 while the shaft continues to revolve. For said mechanical-device to move the worm-wheel into engagement with the worm requires an appreciable length of time, and such time will vary according to speed of 45 shaft of the motor. The worm-wheel has connected with it a spring e^{12} adapted to return it to normal position when disengaged from the worm, said return movement being limited by the pin e^{13} fixed to 50 a suitable support, which is engaged by a stop-pin e^{14} on the worm-wheel. Said worm-wheel is provided with a series of 55 holes, e^{15} , although one only may be employed if desired, and said holes are arranged circularly about its axis, and a large pin e^{16} is adapted to be placed in any one of the holes. Said pin e^{16} moved by the worm-wheel is employed to engage and operate the controlling-device for the electric- 60 switch, which is here shown as a pair of 65

circuit-contacts e^{17} , e^{18} , arranged to control a circuit e^{20} containing a trip-coil t , by which one or more switches may be operated to open the main circuits. One or both of said circuit-contacts is flexible, and they are arranged on suitable supports and adapted to be moved, one into and out of engagement with the other, to close and open the circuit e^{20} , the movable contact-member e^{17} being arranged in the path of movement of said pin e^{16} , so as to be engaged by said pin as the worm-wheel revolves. It will be observed that adjustment as to time may be made by placing the pin in the different holes. 70 75 80

In lieu of the particular form of controlling-device for the electric-switch here shown, other forms may be employed.

Referring again to the overload relays, both of which are or may be made alike, see Fig. 3, the armature or core d^8 has secured to it a non-magnetic rod d^9 , vertically adjusted by a nut d^{10} . The contact-plate d^4 is pivotally connected to said rod d^9 , so as to engage the pair of contacts d^6 , d^8 . Said rod extends through a hole in a pivoted arm d^{12} , and has arranged on its lower screw-threaded end a nut d^{13} , which engages the under side of said arm, so that said arm will be lifted by an upward movement of the core of the relay. Said pivoted-arm bears a contact-plate d^{14} , which is adapted to engage a contact-plate d^{15} , when the arm is raised by an upward movement of the core of the relay, and to disengage said contact-plate when said arm is returned by a spring d^{16} attached to it. Said contact-members d^{14} and d^{15} also control the circuit of the trip-coil t . 90 95 100 105

The operation is as follows: Suppose a current should flow slightly in excess of that required to lift the core of the overload-relay to disengage the contact-members d^6 , d^8 , and slightly extend the spring d^{16} but not sufficient to extend said spring far enough to cause the contact-members d^{14} , d^{15} , to engage, 110 then it will be seen that the shunt-circuit for the motor is open and the motor included directly in the transformer circuit. This will cause the armature of the motor to revolve, and, by means of the mechanical operating-devices connected to its shaft, will cause the worm-wheel to engage the worm. If the excess of current is sufficiently prolonged, the worm-wheel will be revolved until the pin e^{16} engages the contact-member and closes 115 the circuit of the trip-coil to operate the switch, but if the excess of current should not be prolonged sufficiently to accomplish this result, and should cease before the pin e^{16} engages the contact-member e^{17} , then said 120 worm-wheel will be automatically restored to normal position, and the parts will resume their normal positions automatically. Should the excessive current be what is ordinarily 125 called a "short-circuit," the spring d^{16} of 130

the overload-relay will be quickly extended, and the contact-member d^{14} moved into engagement with the contact-member d^{15} , and, as these contacts are arranged in multiple 5 with the contact-members, the trip-coil t will be operated and the switch opened.

The employment of a series-motor, or motor having the characteristics of a series-motor, is of material advantage for the reason that the load is practically constant, and, by keeping the flux density of the magnetic circuit extremely low, the speed of rotation of the motor-shaft will increase with the increasing current through the coils of the motor-armature; that is to say, if the time-limit device is set, so that the switch will be opened in two seconds on a current of five amperes, a lesser period of time would be required to accomplish the same result on a current of 10 ten amperes. In other words, as the current increases, the time required for opening the switch decreases. As a further advantage of my invention the device is entirely automatic in its action; does not require manual 15 re-setting. The employment of an overload-relay, such as here shown, in connection with the time-limit device, for opening the switch instantly, in case the current is a heavy one, is desirable.

20 My invention is equally applicable to a single-phase system, and, in Fig. 5, a diagram of such a system is illustrated, wherein the same elements are employed.

I claim:

35 1. In combination with an electric-circuit having an overload-current relay, of a time-limit device for an electric-switch consisting of a circuit-controlling device for the circuit of said switch, an operating device 40 for said circuit-controlling device requiring a prolonged interval of time for its operation, an electric-motor controlled by the overload-current relay for actuating said operating-device at a variable speed according 45 to the strength of the overload-current, means operated by the motor at a variable speed according to speed of the motor for connecting said operating-device with the motor and means to automatically reset said 50 operating-device to normal when said motor ceases to operate, substantially as described.

2. In combination with an electric-circuit having an overload-current relay, of a time-limit device for an electric-switch consisting 55 of a circuit-controlling device for the circuit of said switch, an operating-device for said circuit-controlling device requiring a prolonged interval of time for its operation, an actuating-member into and out of engagement with which said operating-device is 60 movable, an electric-motor controlled by said overload-current relay for moving said actuating-member at a variable speed according to the strength of the overload-current, and means also operated by said mo-

tor at a variable speed according to the speed of the motor for controlling the engagement of said operating-device with said actuating-member, whereby said operating-device is actuated at a variable speed, and means to automatically reset said operating-device when the motor ceases to operate, substantially as described. 70

3. A time-limit device for electric-switches consisting of a circuit-controlling device for controlling the circuit of the electric-switch, an operating-device for said circuit-controlling device, an actuating-member into and out of engagement with which said operating-device is movable, means operated by 75 the actuating-member for moving said operating-device into engagement with it, and a motor for operating said actuating-member, substantially as described.

4. A time-limit device for electric-switches consisting of a circuit-controlling device for controlling the circuit of the electric-switch, an operating-device for said circuit-controlling device, an actuating-member into and out of engagement with which said operating-device is movable, means operated by the actuating-member for moving said operating-device into engagement with it, means for resetting said operating-device when disengaged from the actuating-member, and a 80 motor for operating said actuating-member, 85 substantially as described.

5. A time-limit device for electric-switches consisting of a circuit-controlling device for controlling the circuit of the electric-switch, 100 an operating-device for said circuit-controlling device, an actuating-member into and out of engagement with which said operating-device is movable, an electric-motor arranged to operate said actuating-member at 105 a variable speed, whereby the operating-device is correspondingly operated at a variable speed when in engagement therewith, and means operated by said motor at a variable speed according to the speed of the 110 motor for moving said operating-device into and out of engagement with said actuating-member, substantially as described.

6. A time-limit device for electric-switches consisting of a circuit-controlling device for controlling the circuit of the electric-switch, an operating-device for said circuit-controlling device, an actuating-member into and out of engagement with which said operating-device is movable, an electric-motor arranged to operate said actuating-member at 115 a variable speed, whereby the operating-device is correspondingly operated at a variable speed when in engagement therewith, and means operated by said motor for moving 120 said operating-device into and out of engagement with said actuating-member, substantially as described.

7. A time-limit device for electric-switches consisting of a circuit-controlling device for 130

controlling the circuit of the electric-switch, an operating-device for said circuit-controlling device, an actuating-member into and out of engagement with which said operating-device is movable, an electric-motor arranged to operate said actuating-member at a variable speed, whereby the operating-device is correspondingly operated at a variable speed when in engagement therewith, means operated by said motor at a variable speed according to the speed of the motor for moving said operating-device into and out of engagement with said actuating member, and means for resetting said operating-device to normal when disengaged from the actuating-member, substantially as described.

8. A time-limit device for electric-switches consisting of a controlling-device for the electric-switch, a rotatable-member for operating it, a rotatable-actuator for said member into and out of engagement with which it is movable, and mechanical means operated by an electric-motor for moving said rotatable-member into and out of engagement with said rotatable-actuator, substantially as described.

9. A time-limit device for electric-switches consisting of a controlling-device for the electric-switch, a rotatable-member for operating it, a rotatable-actuator for said member into and out of engagement with which it is movable, an electric-motor for rotating said actuator, and means, also operated by said motor, for controlling the engagement of said rotatable-member and actuator, substantially as described.

10. A time-limit device for electric-switches consisting of a controlling-device for the electric-switch, a rotatable-member for operating it, a rotatable-actuator for said member into and out of engagement with which it is movable, an electric-motor adapted to rotate said actuator at a variable speed, according to the speed of the motor, and means also operated by said motor for controlling the engagement of said rotatable-member and actuator, substantially as described.

11. A time-limit device for electric-switches consisting of a controlling device for the electric-switch, a rotatable-member for operating it, a rotatable actuator for said member into and out of engagement with which it is movable, an electric-motor for rotating said actuator, means, also operated by said motor, for controlling the engagement of said rotatable-member and actuator, and means for resetting said rotatable-member when disengaged from the actuator, substantially as described.

12. A time-limit device for electric-switches consisting of a controlling-device for the electric-switch, a worm-wheel, a worm for revolving said worm-wheel into and out of engagement with which said

worm-wheel is movable, an electric-motor for revolving said worm at a variable speed, and mechanical means operated by said electric-motor for moving said worm-wheel into engagement with the worm, substantially as described.

13. A time-limit device for electric-switches consisting of a controlling-device for the electric-switch, a worm-wheel, a worm for revolving said worm-wheel into and out of engagement with which said worm-wheel is movable, an electric-motor for revolving said worm at a variable speed, and means operated by said motor for moving said worm-wheel into engagement with the worm, substantially as described.

14. A time-limit device for electric-switches consisting of a controlling-device for the electric-switch, a worm-wheel having means for operating said controlling-device, a worm arranged adjacent to said worm-wheel, into and out of engagement with which said worm-wheel is movable, an electric-motor for revolving said worm at a variable speed, and means operated by said motor for moving said worm-wheel into engagement with the worm, substantially as described.

15. A time-limit device for electric-switches consisting of a controlling-device for the electric-switch, a worm-wheel having means for operating it, a worm into and out of engagement with which said worm-wheel is movable, a shaft bearing said worm, a device operated by it adapted to operate by centrifugal action to move the worm-wheel into engagement with the worm, and means for revolving said shaft, substantially as described.

16. A time-limit device for electric-switches consisting of a controlling device for the electric-switch, a worm-wheel having means for operating it, an electric-motor having the characteristics of a series type of motor, a worm on the shaft of said motor into and out of engagement with which said worm-wheel is movable, a centrifugal acting device arranged on said shaft for moving the worm-wheel into engagement with the worm when the shaft revolves, and a spring for resetting said worm-wheel when disengaged from the worm, substantially as described.

17. In combination with an electric-circuit having an overload-current relay, of a time-limit device for an electric-switch consisting of the circuit-controlling device for the circuit of said switch, an operating-device for said circuit-controlling device requiring a prolonged interval of time for its operation, an electric-motor controlled by the overload-current relay for actuating said operating-device at a variable speed according to the strength of the overload-current, means operated by said motor at a variable speed ac-

cording to the speed of the motor for connecting said operating-device with the motor, means to restore said connecting means when the motor ceases to operate and means to automatically reset said operating-device to normal when said motor ceases to operate, substantially as described.

In testimony whereof, I have signed my name to this specification, in the presence of two subscribing witnesses.

GEORGE A. BURNHAM.
